CONTAINER

Ludwig Roth, St. Louis, Mo., assignor to Handy Containers, Inc., St. Louis, Mo., a corporation of Missouri

Application September 14, 1938, Serial No. 229,839

7 Claims. (Cl. 221—79)

This invention relates to containers designed and adapted to contain plastic compositions, and relates generally to means controlling the ejection of the contents from the container.

An object of the invention is to provide an improved container having an end wall attached thereto formed with a central opening, in combination with a nozzle having a circumferential groove at its inner end receiving the marginal portion of said end wall around said opening and being thereby rotatively supported, a cap rotatively attached to said end wall and having an outer peripheral portion adapted to be manually engaged to rotate said cap, means attaching the inner margin of said cap to said nozzle to rotate the same, and a novel ejector device confined within the container and engaging said nozzle for operation thereby to eject the contents of the container.

Another object of the invention is to provide a container having one end formed with an opening, and novel means for rotatively supporting a nozzle in connection with the marginal portion of said end around said opening, and means connected with said end wall for rotating said nozzle in one direction, as required to operate an ejector to discharge the contents of the container through said nozzle.

Another object of the invention is to provide a novel type of ejector device in a container embodying the essentials of the container before mentioned.

A further object of the invention is to provide a container of the character mentioned having a spiral rod rotatively supported in central position therein and formed with an open frame at its outer end engaging the rotary nozzle of the container for rotation thereby, and an ejector mounted on said rod for operation to eject the contents of the container.

Another object of the invention is to prevent reverse rotation of said rod, and thereby effectively prevent refilling the container after it has been wholly or partially emptied.

Other objects of the invention will be readily apparent from the following description, reference being made to the annexed drawing, in which—

Fig. 1 is a top plan view of a container made in accordance with the present invention.

Fig. 2 is a side elevation of said container.

Fig. 3 is an enlarged vertical sectional view on the line 3—3 of Fig. 1.

Fig. 4 is a transverse sectional view through

the nozzle and the closure cap on the line 4—4 of Fig. 3.

Fig. 5 is a transverse sectional view of the container and the ejector rod on the line 5—5 of Fig. 3.

Fig. 6 is an enlarged sectional view similar to the sectional view of Fig. 3, more clearly showing the construction and arrangement of the rotary nozzle and associated parts.

Fig. 7 is a side elevation of the nut or threaded sleeve screwed upon the ejector rod.

The present invention is embodied in a container comprising an enclosing wall 1 having permanently attached thereto a bottom wall 2 formed with a central bearing 3. The opposite end of the container comprises a wall 4 having an annular outer margin 5 receiving the upper end of the container wall 1 and rigidly attached thereto in order to provide a leak-proof joint between the container 1 and said end wall 4. The end wall 4 is formed with a central opening.

A nozzle comprising a tubular portion 6 is rotatively engaged with the margin of the end wall 4 around the opening therethrough. The nozzle 6 is formed with a circumferential bead 7 seating closely against the outer surface of the end wall 4 around the opening therethrough. A groove 8 is formed around the inner end of the nozzle 6 and receives the inner margin of the wall 4 in order to support the nozzle rotatively in connection with the wall 4. Said groove 8 is formed by bending outwardly the inner marginal end 9 of the tube 6 so that the inner margin of the wall 4 engages in said groove. The clamping and frictional engagement of the bead 7 and end portion 9 of the tube 6 with the wall 4 is quite close, so that a substantially leak-proof joint is provided, but leaving the nozzle 6 free to rotate with respect to the end wall 4. The outer end of the tube 6 may be turned or rolled inwardly to form a bead 10 that strengthens the tube 6 against bending and prevents the formation of a sharp cutting edge at the end of the nozzle.

The operating device for rotating the nozzle 6 comprises a cap 11 rotatively seated upon the end wall 4 and provided with a central opening through which the tube 6 extends. The inner margin 12 of the cap 11 is raised to seat upon the bead 7 of the nozzle and to engage under the inner ends of outwardly extending ribs or projections 13 formed in connection with the nozzle 6. These ribs or projections 13 may be formed by bending the wall of the tubular nozzle 6 to extend outwardly, as shown. The cap 11 is rigidly engaged with the tube nozzle 6 so that

neither can turn independently of the other, but both must be turned together. The outer margin 14 of the cap 11 is in the form of an annular flange encircling and closely contacting the annular outer margin 5 of the end wall 4 and having its edge 15 extending under the margin 5 so as to hold the parts securely in assembled relationship. Thus the end wall 4 is rigidly engaged with the end of the container 1 and the cap 11 is 10 rotatively supported by said end wall 4. The outer periphery of the margin 14 may be knurled, or provided with ribs or the like as shown, in order to provide a grip for the thumb or finger of the user to rotate the cap 11, and thereby the 15 nozzle 6 and the ejector device.

In the embodiment shown, a spiral rod 16 is located at the axis of the container 1 and has its inner end rotatively engaged in the bearing 3 formed in connection with the bottom end wall 20 2 of the container. The outer end of the rod 16 is not of spiral form and is bent to form an open frame 17 having at its inner portion lateral extensions 18 engaging under the inner end of the tubular nozzle 6, so that it is impossible to 25 remove or withdraw the spiral rod 16 from the container. The frame 17 extends into the tubular nozzle 6 and is engaged by any two diametrically opposite projections 19 formed in connection with said tubular nozzle. When the nozzle 6 is 30 rotated by the cap 11 in a clockwise direction, as seen in Fig. 4, the spiral rod 16 will also be rotated.

The ejector shown comprises a wall 20 of any appropriate material or composition fitting within 35 in the container 1 and having close frictional engagement with the inner surface of said container. This will prevent the wall 20 from rotating with the rod 16. A sleeve or nut 21 has a spiral opening therethrough so as to screw onto 40 the spiral rod 16. This sleeve or nut 21 extends through the axis of the wall 20 and has a flange 22 on one end seating or clamping against said wall 20 and fingers 23 in its opposite end bent laterally and engaged with or extended into the 45 wall 20. This effectively prevents the sleeve or nut 21 from turning with the rod 16 and seals the opening through the wall 20 to prevent the passage of the container contents therethrough.

A removable and replaceable closure cap 24 is 50 provided to telescope upon the nozzle 6. The wall of the closure cap 24 very closely engages the ribs or projections 13 in order to hold the closure cap securely on the nozzle but to permit withdrawal thereof when it is desired to eject a 55 portion of the contents of the container 1.

If desired, reverse rotation of the ejector device may be prevented, thereby making it impossible to refill the container or replace any part of the 60 contents thereof.

One or more resilient tongues 25 may be formed 65 in connection with or attached to the cap 11 and caused to engage successively in indentations 26 formed in the wall 4. These tongues 25 will permit turning of the ejector device in a direction to eject the contents of the container, but will prevent turning of the ejector device in the opposite direction to move the wall 20 inwardly toward the bottom wall 2 of the container.

It is now apparent that this invention attains 70 all of its intended objects and purposes efficiently, economically, and satisfactorily. The device may be varied within the scope of equivalent limits without departure from the nature and 75 principle of the invention.

I claim:

1. In a container of the character described having an upper end wall provided with an opening; a tubular nozzle having a groove at its inner end receiving the margin of said wall around said opening and being rotatively supported and held against longitudinal displacement thereby, a cap engaging said nozzle for rotating the same, a device operated by said cap controlling ejection of the contents of said container, and means in 10 connection with the outer margin of said cap engaging said end wall and holding said cap closely against said end wall for rotation thereon.

2. In a container of the character described having an upper end wall provided with an opening; a tubular nozzle extending outwardly through said opening beyond said end wall, portions integral with said nozzle forming a circumferential groove enclosing the margin of said end wall around said opening and rotatively supporting and preventing longitudinal displacement of said nozzle, a device operated by said cap controlling ejection of the contents of said container, and means apart from said portions engaging said nozzle and said end wall for rotating said 20 nozzle.

3. In a container of the character described having an upper end wall provided with an opening; a nozzle mounted in said opening, portions integral with said nozzle forming a circumferential groove receiving the inner margin of said end wall around said opening rotatively supporting and preventing longitudinal displacement of said nozzle in either direction, an ejector within 30 the container, and means apart from said portions attached to said nozzle and said end wall for rotating said nozzle and thereby said ejector.

4. In a container of the character described having an upper end wall, a tubular nozzle extending through and rotatively supported by said 40 end wall, and means attached to said nozzle and supported by said end wall for rotating said nozzle; a spiral rod mounted centrally within said container and having its lower end rotatively engaging and held from lateral movement by the 45 lower end of said container, an integral portion of said rod forming an open frame rigid with the outer end of said rod extending into and engaging said nozzle for rotation thereby, an ejector wall within said container through which said 50 rod extends, and means attached to said ejector wall and engaging said rod whereby said rod will move said ejector wall longitudinally in said container when said rod is rotated by said nozzle.

5. In a container of the character described 55 having an upper end wall provided with an opening, a nozzle extending through said opening and rotatively supported by said end wall, and a cap covering and rotatively engaging said end wall and also engaging said nozzle for rotating the 60 same; a spiral rod located axially within said container and having its lower end rotatively engaging and held from lateral movement by the lower end of said container, an integral portion of said rod forming an open frame at the upper 65 end of said rod engaging within said nozzle for rotation thereby, projections on said frame preventing outward withdrawal of said rod through said nozzle, and an ejector device screwed on said rod for operation thereby.

6. In a container of the character described 70 having a rotary nozzle and means for rotating the same; a spiral rod supported axially within the container for rotation by said nozzle, an ejector wall within the container, a sleeve extending 75

through said ejector wall and screwed on said shaft, a flange on one end of said sleeve clamping against said wall and means integral with the opposite end of said sleeve extending into 5 said ejector wall preventing relative rotation of said sleeve and said wall.

7. A container of the character described comprising an upper end wall having a central opening therethrough, a unitary nozzle extending outwardly through said opening having an outwardly extended flange integral with its inner end en-

gaging the inner side of said end wall around said opening and an integral circumferential bead cooperating with said flange to form a circumferential groove around said nozzle receiving the margin of said end wall around said opening and rotatively supporting and preventing longitudinal displacement of said nozzle, means rotatively mounted on said end wall for rotating said nozzle, and an ejector device in said container operated by said nozzle. 10
